WEATHER STRIPPING

Adolph Rydquist, Rochester, N. Y., assignor to
The Schlegel Manufacturing Company, Rochester, N. Y., a corporation of New York

Application October 24, 1940, Serial No. 362,574

9 Claims. (Cl. 20—69)

This invention relates to weather stripping such as is useful upon windows, doors, and similar movable closures, and has for its principal object the provision of improved and more satisfactory weather stripping of this character.

Another object is the provision of weather stripping so designed and constructed that it either may be installed at the factory making the windows, doors, etc., as original equipment thereon, or may be installed easily and quickly in any existing windows, doors, etc.

Still another object is the provision of weather stripping which requires no nails, screws, or similar fastening means to hold it in place, but which is held merely frictionally, so that it may be easily removed and replaced if it becomes damaged or worn out.

A further object is the provision of weather stripping of such form and dimensions that it may be applied easily to window sash of the usual vertically sliding kind without interfering in any way with the ropes used in hanging or counterbalancing such sash.

A still further object of the invention is the provision of weather stripping of such form that it will make sealing contact with at least two different angularly-disposed surfaces of the associated frame or casing part, to insure effective sealing.

A still further object is the provision of weather stripping so designed and constructed that it will tend to reduce rather than increase the friction of the relatively movable parts with which it is used, and which will have a relatively long effective life.

To these and other ends the invention resides in certain improvements and combinations of parts, all as will be hereinafter more fully described, the novel features being pointed out in the claims at the end of the specification.

In the drawing:

Fig. 1 is a diagrammatic section taken horizontally through a window stile and the associated part of the frame or casing, showing the weather stripping in place;

Fig. 2 is a perspective view of a fragment of a window stile prepared for receiving the weather stripping, and

Fig. 3 is a perspective view of the weather stripping ready to be placed on the stile of Fig. 2.

The same reference numerals throughout the several views indicate the same parts.

As an illustrative embodiment of the invention, the weather stripping is shown in Fig. 1 as applied to a part of a window member such as a

vertical stile 11 of a vertically sliding window sash which, as usual, presents a two-cornered rectangular edge received in a suitable rectangular groove in a casing or frame 13, one edge of the groove being formed by a removable moulding or stop member 15 which can be taken out in order to remove the window. The part of the window shown in Fig. 1 as a stile 11 is merely for the sake of example, as the weather stripping can be equally well applied to the top and bottom rails of the window, to the stiles and top and bottom rails of doors, and in other similar locations. In fact, it is usually preferred to carry the weather stripping all the way around the perimeter of the window sash; that is, up the full height of both stiles, across the bottom of the bottom rail of the lower sash and across the top of the top rail of the upper sash, and also across the meeting or parting rails of one sash or the other. The illustration in the drawing will suffice, however, to indicate how the weather stripping can be applied to any desired stiles or rails or other parts of windows, doors, or other movable closures.

The stile or other part 11 of the window sash which is to receive the weather stripping, is provided adjacent one or both corners with a pair of grooves or slots, such as the groove 21 substantially parallel to the face 23 of the member 11 and spaced a substantial distance from this face 23, also a second groove 25 likewise substantially parallel to the face 23 and located relatively close to this face, as shown. The material between the grooves 21 and 25, preferably is 35 slightly cut back to form a face 27 spaced somewhat inwardly from the plane of the original face 29 of the member 11, approximately perpendicular to the face 23, but a substantial amount of material still remains between the grooves 21 and 40 25 to form a substantial tongue 31. The material between the groove 25 and the face 23 is cut back or cut away through a greater distance, to a face 33, leaving only a relatively short tongue 35.

45 Into the grooves 21 and 25 are thrust the legs or side flanges of a weather stripping member of generally U-shaped form, this member preferably including a stiffening portion or stiffening element having sufficient rigidity to maintain the weather stripping member in its intended shape against any normal displacing forces occurring in ordinary use. The stiffening portion or stiffening element is conveniently made of substantially inert or non-resilient metal, and may take the form of a U-shaped or

channel-shaped sheet metal piece 41 having legs 43 and 45 approximately parallel to each other. The weather stripping member also includes strips of suitable resilient and compressible fibrous material such as the strips of long, stiff textile pile 47 and 49, so arranged as to project beyond the planes of the faces 23 and 29 into weather-sealing engagement with the corresponding angularly-arranged faces of the frame or casing 13. When the stiffening element is of the above mentioned sheet metal form, the pile strips 47 and 49 are preferably woven integrally with a textile fabric strip 51 wrapped over the outer surface of the sheet metal member 41 and held thereon by having the marginal edges of the textile strip 51 clamped firmly by reversely bent portions 53 and 55 on the edges of the metal legs 43 and 45, respectively.

This weather stripping member is placed in the grooves previously formed in the closure member 11, by a lateral motion in a direction parallel to the face 23 of the member 11, thrusting the shorter leg 43 of the weather stripping member into the shallow groove 21 of the member 11 and simultaneously thrusting the longer leg 45 of the weather stripping member into the deeper groove 25. The tongue 31 of the member 11 fits snugly in the space between the legs 43 and 45 of the weather strip, while the thickness of the legs of the weather strip (particularly the thickness of the reversely bent portions 53 and 55) is such as to fit snugly in the grooves 21 and 25, this interfitting of the parts serving to retain the weather stripping frictionally and securely on the closure member 11, while nevertheless permitting it to be pulled off or pried off when necessary. If desired, the pile strip 47 may be wide enough to extend around the corner of the weather stripping member and partly into the slot 21, so that the crowding of this pile into the slot helps to hold the weather stripping frictionally in place. It is usually desirable to provide a break or free space 59 at the corner between the cushioning strips 47 and 49, although the cushioning material may extend continuously around this corner if desired.

It is sufficient in many cases to provide the weather stripping at one corner of the member 11, but it may be desired under some circumstances to provide the stripping along both corners of the thickness of the door or window, and, if so, the groove arrangement is duplicated at the other corner, as shown in Figs. 1 and 2, and a weather stripping member is applied at each corner, as in Fig. 1. This provides a very efficient construction, particularly on the sliding sash of windows. The cushioning strips or elements of the weather stripping contact with the window frame or casing along two zones or lines on the face of the casing which is perpendicular to the plane of the window, and also contact against both of the stops or moldings which are parallel to the plane of the window to prevent movement of the window in directions perpendicular to its plane.

If weather stripping of this kind be carried all the way around the perimeter of the window, and at both corners of the window stiles and rails, as shown in Fig. 1, it is seen that the window is tightly held in its frame or casing by the resilient action of the various cushioning strips, and looseness or rattling in any direction is prevented or minimized. This, however, does not interfere with the opening and closing movements of the window, for the cushioning strips 47 and 49, particularly if made of relatively long,

stiff pile, provide excellent anti-friction surfaces which permit easy sliding of the parts while at the same time making a tight fit and excluding drafts, dust, etc. It will be noted from Fig. 1 that the size of the weather stripping is such that it does not interfere with the window ropes of the usual vertically sliding sash, there being ample room between the two weather stripping members for the usual slot or groove 61 which accommodates the window ropes.

The necessary slots and other cuts for accommodating a weather stripping member of this type can all be made in a single sawing operation using a circular saw composed of a thin blade of one diameter to make the cut 21, a thin blade of a slightly larger diameter to make the cut 25, a thicker blade of smaller diameter to cut the surface 27, and a blade of about the same diameter as the first mentioned blade, to cut the surface 33. When these four saw blades are clamped together on a single shaft or arbor and rotated in unison, on a sawing table provided with suitable guides, it is a very simple matter to move a window sash along the sawing table past the rotating saw blades, in cooperative relation thereto, to make the necessary cut along one corner of any one stile or rail of the window sash, very quickly. This can be done at the sash factory in the case of new sash, or if weather stripping is to be applied to windows already installed in a house, it is a simple matter either to remove the window sash and take them to a local carpenter shop, or to provide a small portable electrically driven saw right on the job. After once the cuts have been made in the sash (or in the edge of the door, when the weather stripping is to be applied to a door) the U-shaped or channel-shaped weather stripping member can be quickly thrust into the proper grooves or slots, and the window or door is then ready to be installed in the usual manner in the frame or casing.

It is a matter of common knowledge that there is considerable variation in the tightness or fit of wooden window sash in the casing or frame. Some sash fit quite snugly between the opposing faces of the casing or frame, while other sash are quite loose. The weather stripping of the present invention is particularly suited to remedying this condition. When weather stripping is to be installed in an existing window, the tightness of fit of the window in the casing is first observed, and the grooves are cut in various positions on the window sash, in accordance with and governed by the tightness of fit. For instance, if the window fits quite tightly in the frame, with practically no lateral play, then the grooves 21 and 25 may be cut slightly deeper, the face 27 being cut correspondingly deeper below the plane 29, so that when the legs of the U-shaped weather strip are thrust home in the grooves 21 and 25, the cushioning material 47 projects only a very slight distance beyond the plane of the face 29. On the other hand, if there is a good deal of side play of the sash in the window frame, then the sawing operation is so performed as to make the grooves 21 and 25 somewhat shallower, in which case the cushioning material 47 of the weather stripping will extend out farther beyond the plane of the face 29, thus in effect adding width to the window so that it is no longer so loose in its casing or frame. When the lateral play of the window is excessive, the grooves may even be cut so shallow that when the side legs of the U-shaped weather stripping are seated on the bottoms of the grooves

21 and 25, the cross portion 41 of the U-shaped member will be offset outwardly beyond the plane of the edge 29, out of contact with the face 27, to increase still further the effective width of the window sash.

The weather stripping of the present invention has been described with reference to mounting on closure members (windows, doors, etc.) made of wood, but the same weather stripping is, of course, adapted for mounting on metal sash, metal doors, or other metal parts, provided the necessary slots or grooves be made in the metal parts.

While one embodiment of the invention has been disclosed, it is to be understood that the inventive idea may be carried out in a number of ways. This application is therefore not to be limited to the precise details described, but is intended to cover all variations and modifications thereof falling within the scope of the appended claims.

I claim:

1. A weather stripping construction including a closure member having two faces at a substantial angle to each other to form a corner between them, two slots extending inwardly from one face of said member, said slots lying substantially in planes parallel to each other and substantially parallel to the other face of said member, a weather stripping member including a base of generally U-shaped cross section mounted on said closure member with the side flanges of said U-shaped member seated in said slots, and cushioning and sealing material mounted on said U-shaped member in position to project from one side wall of said U-shaped member to a position beyond one face of said closure member and from the bottom wall of said U-shaped member to a position beyond the other face of said closure member.

2. A weather stripping construction including a closure member having two faces at a substantial angle to each other to form a corner between them, two slots extending inwardly from one face of said member, said slots lying substantially in planes parallel to each other and substantially parallel to the other face of said member, a weather stripping member including a substantially inert non-resilient base of generally U-shaped cross section having sufficient rigidity to maintain its shape against normal displacing forces in ordinary use, said U-shaped member being mounted on said closure member with the side flanges of the U-shaped member seated in said slots, and cushioning and sealing material mounted on said U-shaped member in position to project from one side wall of said U-shaped member to a position beyond one face of said closure member and from the bottom wall of said U-shaped member to a position beyond the other face of said closure member.

3. A weather stripping construction including a closure member having two faces at a substantial angle to each other to form a corner between them, two slots extending inwardly from one face of said member, said slots lying substantially in planes parallel to each other and substantially parallel to the other face of said member, a weather stripping member including a base of generally U-shaped cross section mounted on said closure member with the side flanges of said U-shaped member seated in said slots, woven textile fabric mounted on the outer surface of said U-shaped member, and textile pile woven into said fabric and projecting outwardly from that portion of the fabric which overlies one side

wall and the bottom wall of said U-shaped base to extend beyond both of said two faces of said closure member.

4. A weather stripping construction including a closure member having two faces at a substantial angle to each other to form a corner between them, said corner being adapted to cooperate with complementary angularly-disposed corner-forming surfaces of a support, two slots extending inwardly from one of said two faces of said closure member and lying approximately in planes parallel to each other and to the other of said two faces, one of said slots being relatively close to said other face and the material between said close slot and said other face being cut away throughout a substantial part of the depth of such slot but not throughout the whole depth thereof, a weather stripping member including a base portion and two side flanges projecting from said base portion at a substantial angle thereto to form a body of generally U-shaped cross section having its side flanges seated in said slots, and cushioning and sealing material mounted on said U-shaped body and projecting from the base portion thereof into contact with one of said corner-forming surfaces of said support and also projecting from one of said side flanges of said body through the opening provided by said cut-away portion of said closure member into contact with the other of said corner-forming surfaces of said support.

5. A weather stripping construction including a closure member having two faces at a substantial angle to each other to form a corner between them, said corner being adapted to cooperate with complementary angularly-disposed corner-forming surfaces of a support, two slots extending inwardly from one of said two faces of said closure member and lying approximately in planes parallel to each other and to the other of said two faces, one of said slots being relatively close to said other face and the material between said close slot and said other face being cut away throughout a substantial part of the depth of such slot but not throughout the whole depth thereof, a weather stripping member including a base portion and two side flanges projecting from said base portion at a substantial angle thereto to form a body of generally U-shaped cross section having its side flanges seated in said slots, and a body of relatively long, stiff, and dense textile pile mounted on said U-shaped body and projecting outwardly from the base portion thereof and from that one of the side flanges thereof which is seated in the slot which is relatively close to said other face of said closure member, said pile making weather-sealing contact with two of said angularly-disposed corner-forming surfaces of said support.

6. A weather stripping construction for window sash provided with a stile having a face bounded by two substantially rectangular corners slidably mounted in a rectangular groove of a casing, said weather stripping construction including four grooves cut in said stile in the face thereof between said two corners, said four grooves being grouped in two pairs of two grooves each, each pair being located adjacent one corner of said stile, and a pair of weather stripping members each of generally U-shaped cross section having side flanges seated in the two grooves constituting one pair, each of said U-shaped weather stripping members including cushioning material on the bottom wall and one side wall of the U-shaped member projecting beyond the planes

of two corner-forming faces of said stile into weather-sealing contact with the corresponding faces of said groove.

7. A weather stripping construction for window sash provided with a stile having a face bounded by two substantially rectangular corners slidably mounted in a rectangular groove of a casing, said weather stripping construction including four grooves cut in said stile in the face thereof between said two corners, said four grooves being grouped in two pairs of two grooves each, each pair being located adjacent one corner of said stile, and a pair of weather stripping members each of generally U-shaped cross section having side flanges seated in the two grooves constituting one pair, each of said members being formed in part of substantially inert non-resilient metal having sufficient rigidity to maintain its shape against normal displacing forces in ordinary use, each of said U-shaped members further including cushioning material on the bottom wall and one side wall of the U-shaped member projecting beyond the planes of two corner-forming faces of said stile into weather-sealing contact with the corresponding faces of said groove.

8. A weather stripping construction for a closure member having two faces forming an approximately rectangular external corner co-

operating with an approximately rectangular internal corner of a casing, said weather stripping construction including two grooves cut in said closure member in one of the corner-forming faces thereof adjacent the other corner-forming face thereof, and a weather stripping member of generally U-shaped cross section having side flanges seated in said two grooves, said weather stripping member being formed in part of substantially inert non-resilient metal having sufficient rigidity to maintain its shape against normal displacing forces in ordinary use and further including cushioning material on the bottom wall and one side wall of said U-shaped member projecting beyond the planes of both of said corner-forming faces of said closure member into weather-sealing contact with the corresponding faces of said internal corner.

9. A construction as described in claim 5, further including textile pile projecting from that side flange of said U-shaped body which is seated in the slot remote from said other face of said closure member, said pile being wedged in said slot when said flange of said U-shaped body is inserted therein, to help in holding said flange firmly in said slot.

ADOLPH RYDQUIST.
